UNITED STATES PATENT OFFICE.

JOSEPH VOGT, OF NIEDERBRUCK, GERMANY.

APPARATUS FOR DEEP BORING.

SPECIFICATION forming part of Letters Patent No. 643,428, dated February 13, 1900.

Application filed March 4, 1899. Serial No. 707,748. (No model.)

To all whom it may concern:

Be it known that I, JOSEPH VOGT, manufacturer, a subject of the German Emperor, and a resident of Niederbruck, near Masmünster, Alsace, Germany, have invented new and useful Improvements in Apparatus for Deep Boring, of which the following is a full, clear, and exact specification.

My invention relates to improvements in apparatus for boring at great depths in which the boring-tool or cutter is rigidly connected to the bore-rod, which is actuated by a rocking beam.

I will describe my improvements with reference to the accompanying drawings, in which, by way of example, they are applied to a construction of boring apparatus in which springs are interposed between the bore-rod and the actuating-beam, as also between this and the driving connecting-rod.

Figures 1 and 2 show, respectively, a side view and a front view of the apparatus, both views being partly in section. Figs. 3 and 4 show, to a larger scale, detail views of parts of the apparatus.

The oscillating beam A, which raises the bore-rod P, is actuated by the connecting-rod B, receiving its motion from the crank-shaft C. The trunnions a of the beam are suspended by means of two screws D D, held by screw-nuts b, carried by the sliding support E, which can be shifted horizontally upon the uprights F by means of a horizontal screw-spindle c, carried in a plate e, fixed to the uprights F. The screw-nuts b are formed as worm-wheels at their periphery and gear with a worm f.

To the uprights F are fixed plates R, having vertical grooves 1 1, 2 2, 3 3 communicating at bottom with a horizontal groove g, and the ends of the trunnions a of the beam are provided with blocks g', which are adapted to slide in one or other of the grooves 1 1, 2 2, or 3 3, into which they may be brought by first shifting them along the horizontal groove

g by means of the screw c and then raising them in the required vertical groove by means of the worm f, which actuates the nuts b of the suspension-screws D. Thus assuming the trunnions a of the beam to be in the position shown in full lines at Figs. 1 and 2, then on turning the worm f they may be brought to the position a', and on then turning the screw

c they can be brought either into the position a² or into the position a⁴. On then again turning the worm f the trunnion of the beam can be brought either to the position a³ or into the position a⁵, these several positions of a being indicated in dotted lines in Fig. 1.

It will be seen from the above description that in shifting the trunnions a of the beam from the grooves 1 1 of the uprights F to the grooves 2 2 or 3 3 (the trunnions having previously been disconnected from the beam in any suitable manner) the stroke of the bore-rod P will be diminished, while if the trunnions a be shifted from the grooves 3 3 to the grooves 2 2 or 1 1 the stroke of the bore-rod P will be increased, so that by this means the action of the boring apparatus can be adapted to suit strata of different hardness through which the boring has to be made without requiring to replace the crank-shaft C by another for imparting to the connecting-rod a different length of stroke, which operation would cause a considerable loss of time. When diminishing the stroke of the bore-rod, its speed can be increased.

The pivot h of the connecting-rod B, Figs. 1 and 4, is fixed in a bearing i, fixed on a plate H, resting on the springs I, which have for their object to deaden the shocks which the connecting-rod tends to impart to the beam on starting the upward motion of the bore-rod. On the plate H rest counter-springs I', and the tension of these springs I and I' can be regulated by means of screw bolts and nuts K. The counter-springs have for their object to deaden the shocks which the beam A tends to transmit to the rod B on the downward or percussive motion of the bore-rod P. Their tension can be regulated by means of the bolts K, according to the weight of the bore-rod—that is to say, according to the depth at which the boring-tool fixed to the bore-rod is acting.

The springs M, Figs. 1 and 3, on which rests the bore-rod P and which have the object of deadening the shocks which the bore-rod tends to impart to the beam A at the free fall of the former, are also combined with counter-springs M', placed beneath the beam A, and the tension of these springs M M' can be regulated according to the weight of the bore-rod by means of screw bolts and nuts N.

The springs M' prevent any sudden upward jerks of the bore-rod when it is being raised. By thus deadening the several shocks to which the apparatus is liable any damage to the bore-rod is prevented, and the speed of working can be increased.

What I claim is—

1. An apparatus for deep boring, having a supporting-frame provided with horizontal grooves, a rocking beam supported in said frame, a boring-rod suspended from one arm of said beam to receive a boring-tool, and operating means coupled to the opposite end of said beam, of two trunnions for the beam, movable along the same in the horizontal grooves in the frame, and a screw for shifting the said trunnions along the frame, whereby the fulcrum of the beam is adapted to be shifted without moving the beam either longitudinally or vertically, substantially as set forth.
2. In an apparatus for deep boring, the combination with the supporting-frame, and the rocking beam mounted thereon, of the connected trunnions of the beam, and screws for raising and lowering the trunnions and for shifting them along the supporting-frame, said frame having, at each side of the beam, a plurality of vertically-arranged keeper-grooves to receive the trunnions, said grooves being connected by a horizontal groove, substantially as and for the purposes set forth.
3. In an apparatus for deep boring, the combination with the supporting-frame, the rocking beam A, and the sliding support E, of the connected trunnions a of said beam, the two upright suspension-screws D D, coupled to the trunnions and having on them wheel-nuts b, the grooved plates on the frame to receive the trunnions, the adjusting-screw c, and the worm f, between and gearing with the wheel-nuts b, substantially as set forth.
4. In a deep-boring apparatus, the combination with the frame, the rocking beam, the connecting-rod coupled to one arm of the beam, the means for operating said rod, and the rigid boring-rod carried freely by the other arm of said beam, of the springs M, interposed between the boring-rod on the upper side of the beam, the counter-springs M', at the lower side of the beam, to prevent the transmission of shocks from the boring-rod to the beam and from the latter to the rod, and screw-bolts N, which extend through the beam and the oppositely-arranged springs, for simultaneously and uniformly varying

the tension of the springs, substantially as set forth.

5. In a deep-boring apparatus, the combination with the frame, the rocking beam, the rigid boring-rod supported freely on one arm of the beam, the connecting-rod B, and means for operating said rod, of the plate H, to which the upper end of the rod B is coupled, the springs I, under said plate and between it and the beam, the counter-springs I' resting on the plate H and opposite, respectively to the springs I, the screw-bolts extending through the beam and the respective springs, and the nuts thereon for regulating the tension of the springs, substantially as set forth.

6. In a deep-boring apparatus, the combination with the frame, the rocking beam mounted therein, the boring-rod coupled to one arm of the beam, the connecting-rod coupled to the other arm of the beam, and means for operating the connecting-rod, of the plate to which the connecting-rod is coupled, the springs between said plate and the beam, the counter-springs on the opposite side of said plate, means for coupling said springs and plate to the beam, and for regulating the tension of the springs, the cushion-springs M, of the boring-rod, the counter-springs M', of said rod, and means for coupling said springs to the beam and for regulating the tension of the springs, substantially as set forth.

7. In a deep-boring apparatus, the combination with the frame, the rocking beam mounted therein, the rigid boring-rod resting freely upon one arm of the beam, the connecting-rod coupled to the other arm of the beam and means for operating the connecting-rod, of the plate H to which the connecting-rod is coupled, the springs I between said plate and the beam, the counter-springs I' on the opposite side of said plate, means for coupling said springs I, I' and plate H to the beam and for regulating the tension of the springs I, I', the cushion-springs M of the boring-rod, the counter-springs M' of said rod, and means for coupling said springs M, M' to the beam and for regulating the tension thereof, substantially as set forth.

In witness whereof I have hereunto signed my name, this 4th day of February, 1899, in the presence of two subscribing witnesses.

JOSEPH VOGT.
